(57) **CLAIM**

The ornamental design for a door handle, as shown and described.

DESCRIPTION

FIG. 1 is a front, top, left side perspective view of a door handle showing our new design;

FIG. 2 is a rear, bottom, left side perspective view thereof;

FIG. 3 is a front, top, right side perspective view thereof;

FIG. 4 is a front elevational view thereof;

FIG. 5 is a rear elevational view thereof;

FIG. 6 is a left-side elevational thereof;

FIG. 7 is a right-side elevational thereof;

FIG. 8 is a top plan view thereof;

FIG. 9 is a bottom plan view thereof;

FIG. 10 is a first perspective view showing the door handle in use; and,

FIG. 11 is a second perspective view showing the door handle in use.

The broken lines shown in the drawings depict portions of the door handle and form no part of the claimed design. The broken lines in FIGS. 10 and 11, showing the remainder of a gate, depict environmental subject matter and form no part thereof.

1 Claim, 11 Drawing Sheets
